United States Patent Office

Des. 186,537
Patented Nov. 3, 1959

186,537

PRETZEL HOLDER

Earl L. Fuller, Ridley Park, Pa.

Application December 15, 1958, Serial No. 53,779

Term of patent 14 years

(Cl. D44—24).

Fig. 1 is a perspective view of a pretzel holder showing my new design;

Fig. 2 is a rear elevational view; and

Fig. 3 is a side elevational view.

A dish is shown by means of broken lines in Figs. 1 and 2 for illustrative purposes.

I claim:

The ornamental design for a pretzel holder, as shown and described.
